(57) **CLAIM**

The ornamental design for a cereal food piece with emoji, as shown and described.

DESCRIPTION

FIG. 1 is a front, top and left side perspective view of a first embodiment of a cereal food piece with emoji showing our design;

FIG. 2 is a front elevational view thereof;

FIG. 3 is a rear elevational view thereof;

FIG. 4 is a right side elevational view thereof, the left side elevational view being a mirror image thereof;

FIG. 5 is a top view thereof, the bottom plan view being a mirror image thereof; and,

FIG. 6 is a front, bottom and right side perspective view of a second embodiment of a cereal food piece with emoji, shown in an environment of use.

The less concentrated stippled shading and more concentrated stippled shading areas shown in FIGS. 1–6 represent contrasting appearances. The dot-dash-dot lines in FIGS. 1–5 illustrate the boundary of the invention and form no part of the claimed design. The broken lines in FIG. 6, depicting a bowl with an abundance of cereal food pieces and a spoon supporting a cereal food piece of our design, illustrate environment that form no part of the claimed design.
